Attorney, Agent, or Firm—Worsham Forsythe Wooldridge LLP

[57] CLAIM

We claim the ornamental design for a decorative coat, as shown and described.

DESCRIPTION

FIG. 1 is a back view of the design; and, FIG. 2 is a front view of the design.

The broken or dashed lines that appear on the claimed invention as shown in the drawings are understood to represent stitching.

1 Claim, 1 Drawing Sheet

FIG. 2
